BINDING DEVICE

Joseph R. Burns, Millbourne, Pa.

Application December 5, 1942, Serial No. 468,005

35 Claims. (Cl. 100—31)

This invention has general reference to instrumentalities or devices primarily designed to apply and fasten bonding medium to and about articles, packages, bundles, bandages, and so forth; and, more particularly, to the species using flexible strip as the medium with appropriate securing means attached to the confronting portions of said medium when brought together and compacted.

The primary object of this invention is to provide a novel instrumentality or device, of the above indicated species, which is capable of multifarious usage, for example in factories, stores, homes, offices, hospitals, and wherever the application of a binding is required or desirable.

Another object is the provision of a binding instrumentality or device which will effect the bonding operation in a simple, efficient and speedy manner by aid of coordinated mechanisms progressively-actuated incidental to co-related movements of inter-pivoted normally-open jaws or bows, with an associated independently-movable actuator.

A further object is to provide an instrumentality or device of the type referred to which is adapted to the binding of units individually or collectively, or multiples thereof coupled together in chain-fashion, and otherwise as desired or required.

A still further object is the provision of a binding device effective to make single loop-bonds in a simple and secure manner with a minimum of labor; as well as to readily duplicate such bonds in multiple.

Furthermore, an additional object is to furnish a binding device of somewhat "plier-like" formation characterized by relatively movable jaws capable of diverse positional assembly, so that the scope of the operative range of usefulness is considerably extended.

Many other objects, with ancillary advantages, of this invention will become apparent from the following detailed explanation of a preferred embodiment thereof, as shown in the accompanying illustrative drawings, wherein like characters of reference designate corresponding parts in all the views; while the concluding claims more particularly define the features of novelty over prior art.

In the drawings:

Fig. 1, Sheet 1, is a face view of a binding instrument or device embodying the present invention in the initially closed or first operative position.

Fig. 2 is a staggered view with parts in section

to better disclose the underlying mechanism, said view being taken somewhat substantially as indicated by the arrows and broken lines II—II in Fig. 1.

Fig. 3, Sheet 2, is a part sectional and part elevational staggered view, taken approximately as conventionally indicated by the arrows and broken lines III—III in Figs. 2 and 4.

Fig. 4 is a staggered longitudinal section, taken as indicated by the arrows and broken lines IV—IV in the preceding figure.

Fig. 5, Sheet 3, is a staggered section through the movable jaw of the binding device taken approximately as indicated by the arrows V—V in Fig. 3.

Fig. 6 is a similar section on the plane VI—VI in Fig. 3.

Fig. 7 is a side view of the binding instrument or device as seen looking from the right to the left hand of Figs. 1 and 3.

Fig. 8, Sheet 4, is a fragmentary part sectional and part elevational view corresponding with the lower half of Fig. 3, but showing the parts as shifted incidental to an initial activation by mechanism hereinafter fully described.

Fig. 9 is a similar view to the preceding with the parts in different position resultant to a further activation.

Fig. 10, Sheet 5, is a vertical section taken approximately within the confines of the broken line rectangle *r* in Fig. 1, but drawn to much larger proportions to better illustrate the enclosed mechanism, as well as including a fragmentary portion of a package or other thing in process of being bound up; the plane of this sectional view being also indicated by the arrows X—X in Fig. 20, Sheet 8 of the accompanying drawings.

Fig. 11 is a similar section within the confines of Fig. 1, but taken on the plane XI—XI in Fig. 20.

Fig. 12, Sheet 6, is a staggered cross-section on the plane XII—XII in Fig. 10.

Fig. 13 is an end elevation of the right-hand jaw end, as viewed in the direction of the arrows XIII—XIII in Fig. 10.

Fig. 14 is a staggered vertical section on the plane XIV—XIV of Fig. 10.

Fig. 15 is an end elevation of the left-hand jaw end, as viewed in the direction of the arrows XV—XV in Fig. 10.

Fig. 16, Sheet 7, is a plan section taken approximately as indicated by the arrows XVI—XVI in Fig. 10.

Fig. 17 is a top plan view of the jaw ends with-

in the confines of the arrows XVII—XVII in Fig. 10.

Fig. 18 is a plan section similar to Fig. 16, but showing the parts in a different position.

Fig. 19 is a plan section within the confines of the arrows XIX—XIX, Fig. 10.

Fig. 20, Sheet 8, is a plan section, taken as indicated by the arrows XX—XX in Fig. 10.

Fig. 21 is a view similar to the preceding with the parts in a different position.

Fig. 22, Sheet 9, is a plan section within the confines of the arrows XXII—XXII in Fig. 10.

Fig. 23 is a top plan view of a trap-door device included in the left-hand jaw portion of Fig. 22.

Fig. 24 is a broken perspective view of a manipulator device and pusher means hereinafter fully described.

Fig. 25, Sheet 6, is a perspective view of spaced gripper and binder medium compacting means, later on fully described.

Fig. 26, Sheet 9, is a similar perspective view of cooperative clinching means, likewise herein-after fully clarified.

Fig. 27, Sheet 6, is an enlarged scale detail view illustrative of the binder fastening effected by instruments or devices in accordance with this invention.

Fig. 28, Sheet 9, is an enlarged scale detail view somewhat corresponding to Fig. 27, but showing a slight modification in locking or clinching the securing strip about the binder bond.

Fig. 29 is a section on the plane XXIX—XXIX of Fig. 28.

Fig. 30, Sheet 4, is a face view illustrative of how the binder medium is initially drawn out to the requisite extent relative to an article or bundle for encircling the same.

Fig. 31 is a similar view illustrative of the manner in which instruments or devices of this invention operate upon compressible goods.

Fig. 32, Sheet 10, is a broken face view of the jaw-head aligning portions of a binding instrument or device, in accordance with this invention, and including guide means effective to prevent lateral slip of the binding medium relative to the article or goods being bound; said view also showing the initial coactive relation of the guide means with respect to the article or goods to be bound.

Fig. 33 is a similar view with the guide means in the active position; and,

Fig. 34 is a top plan view of the preceding figure, with the article or goods removed.

In describing the illustrated embodiment of this invention, in connection with the accompanying sheets of drawings, specific terms will be employed for the sake of clarity, but it is to be understood the scope of said invention is not thereby limited; each such term being intended to embrace all equivalents which perform the same function for an analogous purpose.

For exemplification only, the form of embodiment of this invention illustrated will be hereinafter explained in its capacity as a package binding device; while the term "single" is intended to refer generally to individual articles, parts and limbs of living bodies, as well as inanimate objects and things. Similarly, wherever in the following descriptive matter the term "collective" or its equivalents refers to multiple articles, and so forth, packed together, in bundles, stacked, or otherwise arranged for unit bonding or tying; while it is to be expressly un-

derstood the jaws of the device are normally open when inoperative.

Referring now, more in detail, to the drawings, the novel package binding device therein shown briefly comprises opposing hollow jaws 1, 2, the former of which is hereinafter distinguished as "stationary" while the latter is designated "movable," for purposes of differentiation; as well as an independently movable handle or grasp 3.

10 The jaws 1, 2 are interpivotally mounted, while the former embodies a tubular and rectangular-section part or bow 4, approximately tangential in respect to opposing cup-sections 5, with a suitably-shaped handle or grip extension 6. Somewhat similarly the opposing jaw 2 comprises a rectangular-section bow 7 and opposing cup-section 8, with which the independently movable grasp 3 aforementioned is cooperatively related; while the bow 7 is provided in one face with a movable cover section 9, hinged thereto at 10, providing access to the interior for purposes later on duly set forth, and said cover section is held in closed position by suitable retainer means 11.

15 The aforesaid parts are pivotally mounted in cooperative relation through the medium of an axially-shiftable pin or arbor 12 afforded support in sleeve-like members or devices 13, 14, Fig. 4 more particularly, and respectively comprising attached retainer-flanges 15, 16, as well as embodying relatively-stepped ratchets 17, 18, with intervening spacer sections 19, 20. These spacer sections 19, 20 provide pivotal support for the cup sections 5, 8 of the respective jaws 1, 2 by engagement through central holes 21, 22 therein; and between the inner ends of the devices 13, 14 there are rotatively mounted on the arbor 12, adjoining binder medium tape and securing medium strip supply reels 23, 24, respectively. These reels 23, 24 have associated movement restraining means 25, coactive with the circumferential edges thereof; such means being preferably in the form of spring strips fixed to the lower circumferential walls of the cup portions 8 by attaching means 26, and whereby the reels 23, 24 are restrained against too free rotation, as hereinafter fully explained.

20 In order to provide means whereby the fully wound reels 23, 24 may be readily inserted into, and removed from the binding device, when the respective supply of binder medium, such as paper or fabric tape 21, or the securing strip of metallic foil 28, for example, thereon becomes exhausted, the hereinbefore referred to shiftable arbor 12 is provided at one end with a finger hold 29 which affords means whereby it can be axially moved; and at the other end said arbor 12 is formed with a longitudinal groove 30 for engagement with a corresponding-section positioning tongue or spline 31, in the adjoining portion of the bore of the sleeve device 13. To secure or hold the arbor 12 against rotation when inserted, it is provided with a radial hole 32 for registration with a similar diameter hole 33 through the flange 16, and a lock-pin 34 engages 25 said holes under the influence of a retainer spring 35 attached to the flange 16 by appropriate means 36, while said spring is conveniently formed with a finger projection 37, whereby provision is made for lifting the pin 34, in an obvious manner. In addition, the arbor 12 is provided with spaced radial holes 38, 39 for temporary reception of the inner end part of the lock-pin 34, as later on fully explained.

25 Referring now to the independently movable grasp 3, and as readily understood from Figs.

1-4, more particularly, it will be seen that said grasp is of trough-shape in cross-section with a concavo-convex outer end 40 and parallel eye-ended link portions 41, 42 for pivotal support on the sleeve devices 13, 14 between the bow cup-sections 5; 8; said portions having intermediate their ends inwardly-directed lugs 43, engageable through arcual slots 44 in cup sections 8; and affording anchorage at 45 for one end of an associated recoil spring 46; the other ends whereof are similarly attached to pins 47 in said cup sections. Thus it will be seen the independently movable grasp 3 is spring-influenced outwardly, see: Figs. 3 and 9 to best advantage. The link portion 41 of the grasp 3, as best shown in Figs. 1, 2 and 4, is provided with an extension 48 having a stud 49 affording pivotal bearing for an actuator dog 50, maintained in operative engagement with a twelve-tooth ratchet 51 by a springy-tongue 52 secured within the cup section 5 and engaging the heel 53 of said dog. The ratchet 51, it is to be noted, is housed within a central or auxiliary cup-portion 54 of the cup-section 5; while said ratchet is secured to the spacer section 19 of the sleeve device 13 by a spline or key 55 so that, as the grasp 3 is intermittently moved angularly inwards relative to the stationary jaw grip-extension 6, the respective stepped ratchets 17, 18 are concurrently rotated a definite degree determined by the shape of their teeth and the operatively coordinated, binder-tape and securing-foil 27, 28, feed mechanisms now to be described.

These feed mechanisms being substantially individual and of differential "throw," that associated with the binder tape 27 will first be detailed with reference to Figs. 3-9 more particularly, and from which it will be readily understood said tape, on leaving the reel 23 passes outwardly over a cross portion or bridge piece 56, intermediate the circumferential walls of the cup sections 8, and is threaded upwardly through an appropriate guide tube 57 rigid within the movable-jaw bow 7, as well as the cross-cuts or diametric notches 58 of suitably located stationary guide studs 59 also interior of said bow. Ready accessibility to the jaw-bow interior is afforded by the hinged cover 9; and it will be obvious from Figs. 3 and 5 how the upward threading of the binder tape 27 is effected; it being likewise self-evident said tape is inclined inwards from the guide tube 56 to a central position for entry into the jaw head 60 for purposes hereinafter set forth. Associated with the parts just described is a flexible feeder or pusher 61 afforded suitable guidance along the inner wall 62 of the movable-jaw bow-portion 7. This pusher 61 is conveniently in the form of a flat band having attached to its lower end, by rivets or the like 63, Fig. 5, a yoke or fork 64 embodying a shouldering 65 and spaced legs 66; the latter being formed with camming sections 67 and terminal projections or dog portions 68 for operative coaction with the teeth of the ratchets 17, hereinbefore referred to, whereas the free end parts 69 of such dog portions engage rigid stop-pins 70 in the cup sections 8. It is to be here noted the yoke shouldering 65 serves as an abutment for the engaging end of the pusher 61 to effectively prevent lateral movement thereof; while arcually allocated pins 71, 72, also fixed in the cup sections 8, respectively coat with the camming sections 67 and opposing faces of the spaced legs 66 to accommodate and limit the combined reciprocatory and oscillatory move-

ments of the pusher-fork 64 incidental to operative coaction of the ratchets 17 with the dog portions 68, as hereinafter further amplified.

Somewhat similarly the substantially-narrower securing strip or foil 28, as it leaves the reel 24, passes over the bridge-piece 56 upwards through a guide tube 13 to a plane transformer device 74. This transformer device 74 is preferably in the nature of a flattened arcually-shaped tube having the respective entrant and exit ends 75, 76 twisted into right-angled relation; and said transformer is rigidly fixed within the bow 7 by securing means 77, while the exit end 76 may be longitudinally split at 78, and taperingly expanded, to facilitate withdrawal of the foil 28 therefrom, and for reasons later on again referred to. Associated with the parts just described is a flexible feeder or pusher 79 afforded slidable guidance along the outer wall 80 of the movable-jaw bow-portion 7; said pusher preferably being in the form of a flexed springy flat band having attached at its lower end, as by rivets 81, Fig. 6, a yoke or fork 82 embodying an abutment rib 83 and spaced legs 84, said legs having at their free ends dogging claws 85 and opposingly-directed projections 86, with pins 87 affording anchorage for the one end of recoil springs 88; the other extremities of said springs being correspondingly attached to anchor-studs 89, rigid within the cup sections 8. The dogging claws 85, it will be seen, engage the teeth of the ratchets 18 in opposition to the pull of the springs 88, while stop pins 90, also rigid within the cup sections 8, limit the downward movement, as viewed in the drawings, of the pusher-fork legs 84, in an obvious manner. At this juncture it is well to remark that the flexible-pusher 61 has associated recoil means, conveniently in the form of spiral springs 91 supported by studs 92 rigid within the cup sections 8, such springs having their outer ends anchored at 93 to said cup sections 8 with their inner ends 94 engaging lateral lugs 95, Fig. 5, of the pusher spaced legs 66, in a manner clearly apparent from the drawings.

Referring now to the movable-jaw bow head 60 and the confronting bow head 96 of the stationary-jaw 1 and the more particularly related Figs. 10-15 and 22, it is to be remarked the flexible-pusher 61 is fastened by securing means 97 to the feed device proper, which comprises a shoe 98 having spaced ears 99, affording pivotal connection, by a hinge pin 100, for the spaced apertured part or pivot 101 of a forwardly-projecting binder-tape feed-device 102. This device 102 is formed with a leading cross-piece 103 at a relatively higher level than said device and the ears 101, as well as a central co-planar tongue 104 and a side arm 105 having a downward curvature, for purposes hereinafter explained, and as best shown in Figs. 10, 11 and 22. The hinge pin 100 has rectangular-section ends 106 for sliding engagement in opposing guide-grooves 107 of a housing structure or block 108, snugly fitted in the head 60, and held in place by means further on set forth. A flat spring 109 secured at 110, Fig. 22, to the shoe 98 and engaging on the device pivot 101 serves to maintain the latter normally at rest; while a stirrup-spring 111 having portions 112 coiled around studs 113, projects laterally from the feed-device 102, with the free ends abutting ears 114 integral with said device; whereby the forward end of the binder tape 27 is normally engaged between the cross-portion or loop of said stirrup-spring 111 and the cross-

piece 103 of the feed-device 102, as long as there is any supply to draw from.

The housing structure or block 108 is suitably formed to provide upper and lower, communicating and open-ended, hollows 115, 116, respectively, the former 115 having at one side a connecting slot 117, Figs. 20 and 21, with upper and lower opposing recesses 118, for a purpose hereinafter set forth. Rotative within the upper hollow 115 is a feed drum 119 for the vertically turned portion of the securing-strip foil 28 which is conducted thereto, from the exit end 76 of the plane transformer device 74, by way of an aligned slot 120 in the block 108; and said strip foil is maintained in frictional contact with the feed drum 119 by a coactive roller 121, the axis portions 122 whereof are rotatively journaled in the connecting slot 117, under the influence of inwardly-active centrally-indented leaf-springs 123 engaged at their ends in the opposing upper and lower recesses 118, as clearly understandable from Figs. 12 and 21. The feed drum 119 is fixed on a tubular shaft 124, in turn rotative on a stationary shaft 125 having a head 126 seated in a recess 127 in the lower bridge portion 128 of the block 108, said shaft being restrained against movement by a cap-screw 129, which, it will be remarked, also serves to rigidly secure said block in position within the bow head 60 as hereinbefore premised. Integral with or secured to the lower end of the feed drum 119 is a ratchet 130 operative by an inwardly-influenced angular pawling device 131, pivoted at 132 to an arm 133, integral with the hub portion 134, of the ratchet 130 and feed drum 119, said arm having an aligned part 135, diametrically spaced thereto, and providing pivotal connection at 136 for an actuator link 137, having a slot 138 at its other end, for a purpose later explained.

Referring to the flexible-pusher 79, and as best understood on reference to Figs. 10, 11 and 24 more particularly, it will be seen the leading end thereof is cut-out rectangularly at 139 to define paralleling extensions 140 for seating abutment in a complementally reduced part 141 of a manipulator device, comprehensively designated 142, and to which the flexible-pusher 79 is rigidly connected by rivets 143 for example. This manipulator device 142, as best understood from Figs. 13 and 24, comprises a somewhat channel-section body-portion, one flange 144 whereof being provided with a rectangular-section, for example, slot 145 affording slidable guidance for a cutter member 146; whereas the paralleling flange 147 embodies spaced arms 148, 149, also preferably of rectangular cross-section. The arm 148 embodies a relatively-stepped extension 150 with a vertically-rounded lug 151, for a purpose later explained; while the arm 149 has a similarly-stepped extension 152 with an angularly-related or pendent portion 153, likewise embodying a vertically-rounded lug 154; said portion 153 having secured thereto, by attaching means 155, an angled-tappet 156 with the free extremity rounded at 157, also for purposes hereinafter fully clarified. In addition to the foregoing, the flange 147 of the manipulator device 142 is provided on the inner face with spaced lugs 158, see Fig. 14 to best advantage, having apertures for the reception of the pivot 159 of a trigger 160, under the influence of a leaf-spring 161 attached to the device 142 by securing means 162. This trigger 160 embodies an eccentric tooth 163, see Figs. 10 and 11, for coaction with a stop-tooth 164 in the device 142 for limiting its

turning movement forwardly, as well as a central pin-projection 165 at the outer end remote from the pivot 159, engaging in the slot 138, Figs. 10, 11, 20 and 21, of the actuator link 137 for actuation of the latter, as later on fully clarified.

The cutter 146 is formed with an inclined knife edge 166, Fig. 24, and at the remote end has a hole 167, Figs. 20 and 21, for coupling connection of one end 168 of a retractile spring 169, the remote end whereof being anchored within the bow 7 at an appropriate location (not shown) so as to normally exert an inward pull on said cutter, as readily understandable by those conversant with the art. The cutter 146 is also furnished with a lateral arm 170, Figs. 14, 20 and 21, projecting outwardly through a movement limiting slot 171 in the wall of the bow 7, and terminating with a finger hold 172, whereby said cutter is manually shifted to effect severance of the securing strip or foil 28 as, and when, desired. The actuator-link 137 is provided with a guide projection 173, Figs. 10 and 11, having sliding engagement with the upper face of the manipulator flange 144 to prevent downward movement, and to ensure steady operation of said link; while there is pivoted by a screw 174, Figs. 20 and 21, to the manipulator 142, with interposition of a spring-washer and lock-nut 175, a latching device 176 engageable with a notch 177 in the cutter member 146; said device having an inclined projection 178 whereby it is movable to arrest the cutter 146 in retracted position as later on again referred to.

Seating on top of the housing block 108 and pivoted scissor-fashion to the tubular shaft 124 are cooperative binder-tape narrowing levers 179, Figs. 17 and 18, under the influence of a bow-spring 180 having the ends 181 engaged with the notched-heel portions 182 of said levers; while the remote ends of the levers 179 are formed with arcual serrated and plain sections 183, 184, respectively; said latter sections having curvilinear offsets 185 for coaction with the terminal inner edges 186 of the manipulator spaced arms 148, 149, as later on explained in connection with the operation of the binding device. Stepped guide fingers or prongs 187, best seen in Fig. 16, are secured to the jaw head 60 by suitable means 188 with the forward portions seating in slots 189 with projection beyond the outer end wall of said jaw head, as visible also in Fig. 11.

Referring now to the head 96 of the stationary or receiving jaw 1, and referring more particularly to Figs. 10, 11 and 15, said head has rigidly secured therein upper and lower spaced shelves 190, 191, respectively, for support of mechanisms, now to be detailed. Seating in a recess 192 in the lower shelf 191 is the head 193 of a stationary shaft or arbor 194 secured against rotation by a cap-screw 195, and said arbor affords pivotal bearing for a tubular shaft 196 seating on the lower shelf 191 with free passage through the upper shelf 190. Freely pivoted on the tubular shaft 196 above the self 190 are cooperative scissor-like tape narrowing levers 197, Figs. 17 and 18, under the influence of a bow-spring 198 having its ends engaged at 199 in the notched heel portions 200 of said levers; such levers having arcual serrated and plain sections 201, 202, respectively, for operative coaction with the planarly opposing levers 179. In connection with the levers 197, spaced stops 203 are provided on the shelf 190 to limit their degree of opening; while it is to be here particularly remarked that both

the levers 179 and levers 197 are respectively formed with outset teeth 204, 205 for clinching action upon the securing strip or foil 28, as later on fully clarified.

Operatively coordinated with the levers 197, are coupler-rods 206 rigidly attached to the heel-portions 200 and the corresponding portions 207 of somewhat similar compacting-levers 208, Fig. 25, seating on the lower shelf 191 and pivotally engaging the tubular shaft 196. These compacting-levers 208 are conveniently not spring-influenced, owing to their rigid connection by the rods 206 to the levers 197; while their outer ends are arcually plain surfaced and formed with grip notches 209 for clamping the compacted binder tape 27 below the securing strip or foil 28 during application of the latter. Intermediate the upper shelf 190 and the top faces of the compacting-levers 208, and having free pivotal connection on the tubular shaft 196, are spacedly-related spiralizing and securing-foil severing-jaws 210, 211—Fig. 26—respectively, with an intervening stationary and coactive striker-member 212, functional to initiate coiling of the free end of the securing strip or foil 28 by its concaved outer end 213, Figs. 20 and 21, and following engagement around the previously narrowed and spiralized binder strip 27. The spiralizing and foil-severing-jaws 210, 211 are, respectively, below and above the striker-member 212 with the outer end 213, of said member, engaged in a complementary groove 214 provided for its reception in the flanged active end 215 of the severing-jaw 210, such end 215 being preferably of the vertically-grooved section, best shown in Figs. 20 and 21, to define a claw portion 216, the function of which will be later on set forth. On the other hand, the severing-jaw 211 seats on the striker-member 212 and is preferably formed with a shearing edge 217 inclined to the vertical, see Fig. 15, said jaw being coordinated with the spiralizing-jaw 210 by means of a coil spring 218, one leg 219 whereof engages said severing-jaw and the other leg 220 abuts the spiralizing-jaw 210; while said jaws 210, 211 are respectively provided with laterally-directed cam-projections 221, 222, for related coaction with the manipulator vertically-rounded lugs 151, 154; and in addition the severing-jaw 211 is formed with an arcually-reduced part defining a stop 223 for abutment by the confronting edge 224 of the spiralizing-jaw 210.

Movably mounted in the open end of the jaw-head 96 intermediate the shelf 191 and confronting wall of said head is a frame structure 225, of somewhat channel-section formation, and including upper and lower flanges 226, 227, respectively, said flanges not extending wholly across the jaw-head, with the upper 226 projecting beyond the lower 227, as clearly shown in Fig. 15; while said upper flange 226 is appropriately bent down to define a guide 228. Integral with the flange 227 is an apertured upstanding section 229, which affords, with an aligned hole in the web of the structure 225, limited rotary bearing for a trap-door device 230. This device 230 embodies reduced end extensions or stub-axes 231, 232 whereby it is journaled in an obvious manner, and it also embodies spaced arms 233 having rectangularly-related extensions 234 with the outer faces thereof roughened at 235 for grip engagement on the binder tape 27 against the under-side of the flange 226, previously referred to; and one of said extensions 234 is provided with a laterally-projecting rod 236, see Figs. 22 and 23, for a purpose later on set

forth. For normally holding the device 230 in the position shown by Figs. 10 and 15, or closed with respect to the jaw-head end 96, use is made of a recoil spring 237 having one end anchored at 238 in the block or plate 229 and the other end similarly connected at 239 to said device 230. The stub axle 231 is fitted with a milled knob 240 whereby the device 230 can be manually rocked, while both axles 231, 232 are afforded guidance in slots 241 in the adjoining jaw-walls, as readily understood from Figs. 1 and 15.

Movable in a medial slot 242 through the inner wall 243 of the jaw-bow 4 are opposingly-related manipulators 244, each conveniently comprising a substantially circular grip-section 245 with a central cup 246, a stub 247 slidable along the associated slot 242, and a retainer shank 248 engaged in a correspondingly-sectioned hole 249, Fig. 10, in the lower flange 227, with the terminal wider T-section 250 clinched over into abutment against said flange; while a coil spring 251 seats in the opposing cups 246. Now, it will be readily apparent that by grasping the circular sections 245, the frictional hold of the outer faces of the manipulators 244 against the confronting lock-notches 252 in the opposing faces of the slot 242, can be released, and the entire device 230 slid outwardly by engagement of the stubs 247 in the slot 242 to approximately the dot-and-dash line position indicated at the left-hand side of Fig. 3, whereby any desired length of the binder tape 27 can be manually withdrawn. Incidentally it is to be noted the outer arcual wall, of the jaw-bow 4, is removed between the points 253, Fig. 3, to facilitate the operation just set forth; while the jaw-wall facing the reader is furnished with an open-ended slot 254, through which the tape 27 may be laterally drawn for better grippage between the fingers to aid withdrawal of said tape 27.

The binder-tape reel 23 preferably has the flange edges milled at 255, Fig. 2, for manual rotation, as later on explained, to take up any excess tape 27; while an eccentric cam 256, journaled between apertured ears 257 on the jaw 2 in confronting relation to the bridge-piece 56, and provided with a radial finger 258, may be provided to temporarily arrest or stop further paying-out of the binder tape 27, when the desired or required length has been withdrawn by way of the slot 254 as above set forth.

In order to make provision for using the device of this invention in connection with exterior and larger supplies of the tape 27 and foil 28, there is mounted on a separate bridge-piece 56', Figs. 1, 3 and 7, by securing means 259, a spring grip 260 preferably in the shape of a split pin to prevent any recoil action of said tape, see Fig. 7 to best advantage; while said bridge-piece 56' is formed with slots 261, 262 for entry of the binder tape 27 and securing coil 28, respectively.

Aligned and coactive with the stepped guide-prongs 181, in the jaw-head 6, are what may be conveniently termed hold-down devices 263, Figs. 11, 12, 13 and 16; said devices being slidable in recesses 264 provided for their reception in the head 96. Each device 263 embodies a latch-head 265 for engagement with an outward movement-limiting abutment-portion 266 in the recesses 264; while the opposingly-disposed devices 263 are held in operative relation by a strap 267, Figs. 11, 15 and 16, secured across the head 96 by appropriate means 268, in an obvious manner. The devices 263 are under the joint influence of a buffer-spring 269 including a medial loop 270 en-

gaged over a prong 271 integral with the outer wall of the head 96 below the strap 267. By alignment of the devices 263 with the downwardly stepped portions 272 of the guide-prongs 187, it will be apparent the several levers 179 and 197 are prevented from lifting, or relative upward flexure; while it is to be further remarked the inner edges of the prongs 187 and devices 263 have opposingly inclined edges 273, 274, respectively, for a purpose hereafter set forth.

In addition to all of the foregoing and in order to effectively prevent any excess binder tape, as well as for supporting bunched articles or things, from falling in between or getting pinched by the confronting end faces of the jaw heads 60 and 96 during closure, use is preferably made of the guard means shown in Figs. 32-34, inclusive. This means conveniently comprises a spring wire guard 275 carried by the head 96, and coactive flanking guards 276 pivotally supported in loop offsets 277 of the head 60. The guards 276 each embody a stem 278 with a stop shoulder 279 and an open angularly-shaped head 280, while the lower portion 281 of said stem is inwardly bent at right-angles to the plane of the head 280, for engagement by the curvilinearly flexed tongue 282 of a leaf-spring 283 secured to the underside of the jaw 60 by suitable means 284. On the other hand, the guard 275 embodies relatively spaced coils 285 with a connecting loop 286, whereby said guard is attached to the head 96 by a clamp-screw 287, with the coils 285 partially engaged in an opening 288 provided for their reception in the crown of said head. From the coils 285 extend divergent portions 289 with spaced arcual continuations 290 and straight extensions 291, with terminal angularly-contoured loops 292; said extensions 291 and loops 292 being outwardly stepped for overlap with the heads 280 of the guards 276, as clearly shown in Fig. 34. Upward movement of the guard 275 is limited by lugs 293 conveniently integral with the head 96; while it will be readily understood that the guard portions 281 may be suitably connected in alignment below the head 60 for upward influence by a single spring tongue 282. It is to be further noted that the stop shoulders 279 by sliding engagement with the adjoining side walls of the head 60 effectively prevent rotation of the respective guards 276.

Having explained the structure of the improved binding device of this invention, the use and operation thereof will now be described, it being again emphasized that normally the jaws 1, 2 are open. Now it will be readily seen that in accordance with the size of the device and the extent of normal separation of the jaw heads 60, 96, the bows 4, 7 can be readily passed about any article, such as typically indicated by the reference *a*, Figs. 10, 11, 30 and 31, or bunch of articles as similarly designated *b* in Figs. 32 and 33, capable of entry between the confronting ends of said jaw heads. The user now draws the grasp 3 towards the grip extension 6 of the stationary jaw 1 with initial closure of the jaws 1, 2, and concurrent operation of the pawling means 49-51 as hereinbefore explained, with incidental rotation of the ratchets 17, 18 counter-clockwise and resultant projection of the binder tape pusher 64 from the position of Fig. 3 to that of Fig. 8, as restricted by the stop pins 70, 72, with the dog portions 68 of said pusher ready for snap release from the associated ratchet teeth, and return of the pusher 64 under action of the spiral springs 91. Projection of the pusher flexible component 61 forwardly moves the shoe 75

98 and associated binder-tape grip 102 from the full-line position of Fig. 10 to the dot-and-dash indication in said figure with consequent rocking of the trap-door device 230 on its stub axles 231, 232 angularly-forward in the head 96 by impact of the outer end of the side arm 105 of the grip 102 against a projection 230'-Figs. 10, 22 and 23-flanking the relatively confronting arm 233 of the device 230, as typically indicated by dot-and-dash lines, also in Fig. 10, and placement of the free end of the binder tape 27 in position for snap grippage against the underside of the flange 226 by the roughened faces 235 of the spaced arms 233 when released for "fly-back" action by the recoil spring 237, and return of the pusher 61 to its normal position under snap action effected by the springs 91.

When pressure on the grasp 3 is released said grasp will return to its normal position under recoil action of the springs 46, while the stepped ratchets 17, 18 having been concurrently rotated a definite degree, incident to the initial opening of the jaws 1, 2, a length of the binder tape 27 will have been drawn out sufficient to span the jaw heads 60, 96, or as indicated by the letter *c* in Fig. 30, in opposition to the stirrup-spring 111 as it discharges from the reel 23 under guidance of the tube 57 and stud-notches 58. The jaws 1, 2 are now closed a second time which draws the length of binder *c* intervening the jaw heads 60, 96 snugly, as conventionally indicated by broken and full lines in Fig. 31, around the article *a*. Concurrent with this second closure of the jaws 1, 2, the ratchets 17, 18 are again incrementally turned counter-clockwise by the pawling means 49, 50, 51, with incidental forward projection of the flexible pusher 79 and the attached manipulator device 142, by operative coaction between the dogging claws 85 and the engaged teeth of the ratchets 18, as clearly understandable from Fig. 9, more particularly. Movement of the manipulator device 142 initiates re-opening of the trap-door device 230 by engagement of the tappet 156 with the lateral rod 236 of said device and closure of the binder tape narrowing levers 197 and 208 by respective coaction of the rounded inner edges 186 of the spaced arms 148, 149, with the lever curvilinear offsets 185, and actuation of the levers 208 by aid of the rigid coupler rods 206; while the cutter member 146, due to the latched connection at 176, 177 is caused by its inclined knife edge 166 to shear-off the length *c* from the main binder-tape 27 during the early part of the forward movement of the manipulator device 142, in order to facilitate the narrowing operation, see Figs. 10 and 11. During the further forward movement of the manipulator device 142, the securing foil 28 is advanced by the feed drum 119 under rotative motion imparted by the pawl 131, ratchet 130 and associated parts 133-136 through operative coaction of the pin projection 165 and actuator link 137, as hereinbefore described, and clearly apparent from the drawings, while said foil 28 is caused, by turning action set up by the concaved outer end 213 of the striker member 212 as previously explained, to wrap around the mid-region of the crushed-in part of the binder tape 27 previously narrowed by the levers 197, 208; whereupon the compacting and foil severing jaws 210, 211 are respectively closed inwardly by engagement of the rounded lugs 151 and 154 with the cam projections 221, 222, as readily understandable from Figs. 20 and 21 more specifically, and whereby the bond is completed by

compact coiling overlap of the tape 27 and strip foil 28. Incidentally, it is to be particularly observed the inclined shearing edge 217 of the jaw 211 coacts with the sharp confronting edge of the foil slot 120 to effect a clean cut as readily understandable by those conversant with the art. Furthermore, and as a result of this second closure of the jaws 1, 2 with the full forward movement of the manipulator device 142, the binder ribbon trap-door device 230 will be held open by the tappet 156 engaging the lateral rod 236 as shown in Fig. 11 and, as the manipulator device 142 is snapped back to normal position under the recoil action of the spring 169 by virtue of the latched connection between the parts 146 and 176, said trap-door device will be closed by recoil action of its associated spring 237; whereupon release of the grasp 3 places the device in open position ready for the succeeding binder operation.

When it is desirable that the securing foil band 294, Figs. 28 and 29, be locked against accidental loosening, the claw 216 of the spiralizing jaw 210 is provided on its inner face at the most desirable point with a barb or cutter prong 295 effective to pierce the overlapping ends 296, 297 of said band and thus form an interlock 298, as clearly understandable from Figs. 28 and 29, whereby a tight bond about the narrowed and compacted binder tape 27 is positively ensured. It will also be apparent, without further elaboration herein, how the guard 275 and opposed flanking guards 276 jointly coat and support bundles *b*, by interlapping of their respective angular heads 280 and 292, as well as preventing objectionable lateral movement of such bundles during the bonding operation. This adjunctive means is highly desirable when handling plant stems and other bunched articles or things in restraining them from falling in between and getting pinched by the confronting end faces of the jaw heads 60, 96 during the closure operations.

Another advantage inhering to this invention is that packaged articles and bundles bonded by the means hereinbefore described can be finished off with a bow-tie, so prevalent for "gifts" by drawing out a sufficient length of the binder tape 27; then by disengaging the cutter member 146 from the manipulator device 142 by lifting the latch 176 with the finger of one hand inserted through the aperture 299, said cutter member is retracted by the recoil spring 169 out of operative range. Upon again closing the jaws 1, 2 for the second series of operations, above fully explained, when the heads 60, 96 again separate it will be evident that a further length of the binder tape 27 can be withdrawn and a "bow" tied after the cutter member has been manually projected by the finger hold 172 to sever the tape from supply. Still further, it will be apparent that "multiple-winding" of the tape 27 around the article *a* or bundle *b* can be effected with ease and facility by simply drawing out enough binder tape 27 to make the desired number of wraps around the article, package and so forth, and disengaging the cutter member 146 as just previously explained. Again it will be likewise understood that when fresh supply reels 23, 24 are needed, the user simply raises the lock pin 34 and draws out the arbor 12 by aid of the finger hold 29 until said pin enters the hole 38 for removal of the reel 23, or enters the hole 39 for removal of the reel 24; and obviously such movements will be reversed on making replacements.

While one practical and preferred embodiment of this invention has been fully explained in connection with the illustrative drawings, it will be understood that said invention is not limited thereby but is capable of a variety of other mechanical expressions; and that changes may be made in the form, details of construction and arrangement of parts without departing from the spirit of such invention. Reference is, therefore, to be had to the following claims for a definition of the limits and scope of the inventive concept hereinbefore disclosed.

Having thus described my invention, I claim:

1. A binding device comprising normally-open relatively stationary and movable interpivotized jaws; actuator mechanism for moving the pivotal jaw towards the stationary jaw; means effective to return the pivotal jaw and actuator mechanism to normal position; means supplying binder and securing media through the one jaw to its head; means in said head for projecting the free end of the binder medium therebeyond incidental to initial closure of said jaws; means for gripping the projected free end of the binder medium to withdraw the latter from supply concurrent with re-opening of the jaws; means effective upon the following closure of the jaws to clasp the terminal portions of the withdrawn length of binder medium, after the latter has been placed around the article to be bound, with accessory compacting of said terminal portions; means for severing the binder medium beyond the compacted part thereof; and operatively coordinated means effective to advance and clinch the securing medium around the binder compacted part and to sever the clinched portion from the supply thereof.

2. A binding device comprising normally-open relatively stationary and movable interpivotized jaws, actuator mechanism for closing the movable jaw towards the stationary jaw; means effective to return the movable jaw and actuator mechanism to open position; individual means supplying continuous binder tape and securing strip through the one jaw to its head; means in said head for projecting the free end of the binder tape therebeyond incidental to initial closure of said jaws; means in the head of the opposing jaw for gripping the projected free end of the binder tape to withdraw the latter from supply concurrent with re-opening of the jaws; means in the last mentioned jaw head effective upon the following closure of the jaws to clasp the terminal portions of the withdrawn length of binder tape, after the latter has been placed around the article to be bound, with accessory lateral compacting of said terminal portions; means in the first mentioned head for severing the binder tape beyond the compacted part thereof; and operatively coordinated means effective to advance and clinch the securing strip around the binder compacted terminal portions and to sever such clinched portion of said securing strip from the supply thereof.

3. A binding device as claimed in claim 2, further characterized by means permitting withdrawal of any desired length of the binder tape from supply in excess of that effected by initial closure and re-opening of the jaws; means whereby any over-excess of said binder tape is returnable to supply; and means for arresting the withdrawal as and when desirable.

4. A binding device as claimed in claim 2, further characterized by, a spring grip preferably in the form of a split-pin, mounted on the sta-

tionary jaw, effective to prevent recoil action of the binder tape and securing strip when supplied to the device from an external source of supply.

5. A binding device as claimed in claim 2, further characterized by coactive guards flankingly mounted on and projecting beyond the respective jaw heads, said guards embodying loop portions serviceable to support bundles to be bound, means influencing the guards outwardly, and means limiting rotary and axial movement of such guards.

6. A binding device comprising normally-open relatively stationary and movable inter-pivoted jaws with actuator mechanism for closing the movable jaw towards the stationary jaw; means effective to return the movable jaw and the actuator mechanism respectively into open and inactive position; individual supply means carrying continuous binder tape and securing strip for conduction through the movable jaw to its head; movable means in said head for projecting the free end of the binder tape therebeyond incidental to an initial closure of the jaws; trap means in the head of the stationary jaw adapted to grasp the projected free end of the binder tape and withdraw same from supply concurrent with re-opening of the jaws; coactive normally-open devices in the stationary jaw head operative, upon the following closure of the jaws to clasp the terminal portions of the withdrawn length of binder tape, after the latter has been placed around the article to be bound, with accessory lateral compression of said terminal portions; cutter means in the movable jaw head operative to sever the binder tape beyond the compressed terminal portions; means operatively coordinated with said cutter means actuatable to advance the securing strip into the region of binder tape compression for concurrent overlap and clinching therewith by the aforesaid coactive normally-open devices; and means for severing the requisite length of securing strip from supply incidental to overlap and clinching of such length of said securing strip around the compressed binder tape.

7. A binding device comprising normally-open stationary and relatively pivotal hollow jaws; actuator mechanism for moving the pivotal jaw into closed position; means effective to return the pivotal jaw and the actuator mechanism respectively into open and inactive relation; individual reels for supply of continuous binder tape and securing strip with means for conduction thereof through the pivotal jaw to its head; a reciprocatory device in said head for projecting the free end of the binder tape therebeyond incidental to an initial closure of the pivotal jaw; a movable trap device in the head of the stationary jaw adapted to grasp the projected free end of the binder tape and withdraw same from supply concurrent with re-opening of the pivotal jaw; coactive normally-open narrowing devices in the stationary jaw head operative, upon re-closure of the pivotal jaw to clasp the terminal portions of the withdrawn length of binder tape, after the latter has been placed around the article to be bound, with accessory compacting of said terminal portions; a cutter in the movable jaw head operative to sever the binder tape beyond the compacted terminal portions; feed mechanism operatively coordinated with said cutter actuatable to advance the securing strip into the region of the compacted binder tape with concurrent overlap and clinching therewith by the 75

aforesaid normally-open narrowing devices; and means for severing the requisite length of securing strip from supply incidental to its application about the compacted binder tape.

8. A binding device comprising a normally-open rigid and a connected-pivotal hollow jaws fulcrumed relative to a common arbor; actuator mechanism operative by an independent grasp, coordinated with said arbor, for moving the pivotal jaw into closed position; means effective to return the pivotal jaw and said actuator mechanism respectively into the open position, and inactive location; individual reels for supplying continuous binder tape and securing strip freely journaled on the arbor aforesaid; means for conducting the tape and strip through the pivotal jaw to its head; sleeve and ratchet means providing bearing for the arbor; means permitting individual removal and replacement of such reels; a reciprocatory device in said head for projecting the free end of the binder tape therebeyond incidental to an initial closure of the jaws; means operatively coordinating the last-named device with the sleeve and ratchet means; a pivotal trap-door device in the head of the rigid jaw adapted to grasp the projected free end of the binder tape and withdraw same from its supply reel concurrent with re-opening of the jaws, to provide a length of binder strip adapted to embrace an article for binding the latter; coactive normally-open binder tape gripping-and-narrowing devices in the rigid jaw head operative, upon re-closure of the pivotal jaw to clasp the terminal portions of the article-embracing length of binder tape, with accessory compacting of the abutting tape terminal portions; a carrier with a relatively movable cutter and associated manipulator slidable in the head of the pivotal jaw, said cutter being operative to sever the binder tape beyond the compacted part; means operatively coordinating such carrier with the sleeve and ratchet means aforesaid; means for disengaging the cutter from the carrier; securing strip feed mechanism associated with the carrier and actuatable by the manipulator to advance the free end of the securing strip into engagement with the compacted binder tape for concurrent overlap and clinching therewith by the aforesaid narrowing devices; and means for severing the requisite length of securing strip from supply incidental to its application about the compacted binder tape.

9. A binding device in accordance with claim 8, further characterized by one of the gripping-narrowing and compacting devices including a prong effective to interlock the securing strip overlapping ends together.

10. A binding device in accordance with claim 8, wherein the trap-door device includes means for effecting its reciprocation along guides in the rigid jaw to draw-out an additional length of binder strip, to that limited by normal opening of the inter-pivoted jaws, for the purpose specified.

11. A binding device in accordance with claim 8, wherein the respective supply reels of continuous binder tape and securing strip are mounted on an axially-shiftable arbor, and means whereby the said arbor is arrestable in different positions for individual removal for replenishment.

12. A binding device in accordance with claim 8, further characterized by an arrestor device to stop feed of the binder tape as and when desirable.

13. A binding device in accordance with claim 8, further characterized by a spring grip in the form of a split pin effective to prevent recoil action of the binder tape and securing strip.

14. A binding device in accordance with claim 8, further characterized by spring-influenced movable guards flanking each side of the jaw heads, and means limiting the movements of said side guards.

15. A binding device as defined in claim 8, wherein the stationary jaw embodies a rectangular-section tubular bow and a grip extension, both of which are approximately tangential to an intervening cup-section; the pivotal jaw comprises a similar bow and supplemental cup-section; and the independently movable grasp includes apertured portions for its pivotal support on the ratchet sleeves; an extension lug on one apertured portion having a lateral stud with a spring-influenced actuator dog pivoted on said stud; and a tooth-gear fast on the associated ratchet sleeve portion for intermittent movement by the actuator dog to effect forward movement of the binder tape feed device after initial closing of the pivotal jaw.

16. A binding device in accordance with claim 8, wherein the sleeve and ratchet means are spacedly mounted on the common arbor with retainer flanges at their outer ends, and each embodies relatively-stepped ratchets at the inner end; the individual supply reels of binder tape and securing strip are freely mounted on said arbor intermediate the ratchets aforesaid; there is a spline connection between one sleeve-ratchet means and the arbor at one end of the latter, and a finger-hold at the other end of said arbor; a spring-influenced lock-pin engages through registerable radial holes in the retainer flange, sleeve and arbor, adjoining the finger-hold for restraining said parts from rotation; and there are longitudinally-spaced radial-holes in the arbor for individual coaction with said lock-pin, as desired, to permit insertion and removal of the respective supply reels.

17. A binding device in accordance with claim 8, wherein the binder tape reel is provided with milled circumferential edges for back-racking, and a fixedly mounted leaf-spring device engages across the milled edges of each supply reel for restraining free rotation thereof.

18. A binding device in accordance with claim 8, wherein the actuator mechanism independent-grasp includes lateral lugs; the pivotal jaw has movement-limiting arcual slots in its opposing cup-sections; and associated coil springs have their one ends attached to said lugs with their other ends anchored in said cup-sections.

19. A binding device in accordance with claim 8, wherein the means for conducting the binder tape through the pivotal jaw to its head comprise a guide tube and associated bridge at the entrant end thereof, suitably allocated studs in the pivotal jaw with cross-cut grooves in their outer ends for guiding reception of the binder tape; and a hinged-cover along one side of said jaw affords access thereto for threading the binder tape through the stud grooves.

20. A binding device in accordance with claim 8, further including apertured ears projecting from the pivotal jaw, and an eccentric cam having a manipulator finger is rotatively mounted in said apertured ears, said cam serving to stop feeding of the binder tape when desirable or required.

21. A binding device in accordance with claim

8, wherein the reciprocatory device for projecting the binder tape free end outwardly of the pivotal jaw comprises a shoe, means affording reciprocatory guidance for said shoe in the jaw head; a forwardly projecting device pivoted to the shoe and embodying a cross-piece with a central tongue, a downwardly-directed side arm at one end of the cross-piece, a leaf-spring carried by the shoe and engaging the pivotal de-

10 vice normally maintains the latter at rest; a stirrup-spring including coiled sections engaged on studs rigid with the pivotal device, said spring having its loop portion coactive with the cross-piece of the pivotal device to grip the leading 15 end of the binder tape, lateral projections from the pivotal device for abutment by the outer ends of the spring coils to maintain the loop portion in active position; pusher means whereby the reciprocatory device is forwardly moved; 20 and recoil means whereby said pusher means is retracted after each forward movement.

22. A binding device in accordance with claim 8, wherein the means operatively coordinating the reciprocatory device with the pivotal jaw

25 actuator mechanism comprises a flexible pusher, means affording guidance in said jaw for the pusher with its leading end attached to the reciprocatory device; a fork embodying spaced legs and means for attachment thereto of the 30 other end of the flexible pusher, said leg ends embodying dog sections for coaction with one corresponding series of teeth of each sleeve and ratchet means, cam projections on the fork legs engageable by arcually-located pins in the cup 35 sections of said jaw and serving to maintain the leg dog sections in engagement with the ratchet teeth; stop pins for abutment by the heel portions of the fork leg dog sections to limit retraction of the reciprocatory device, and re-coil 40 springs supported by studs in the respective cup-sections, each said springs being anchored at one end in the associated cup-section and having the other end attached to a lateral lug on the proximate fork leg.

45 23. A binding device in accordance with claim 8, including in the head of the pivotal jaw a relatively stationary structure embodying spacially related and communicating open-ended hollows, a slot connecting into one of the hollows,

50 a pressure roller rotatively journaled in said slot, means inwardly-influencing said pressure roller, a feed drum in one of the hollows with an associated ratchet in the other hollow, pivot means affording free rotary bearing for said drum and 55 ratchet in the stationary structure with projection beyond the latter, pawling means associated with the feed drum and housed in the last mentioned hollow, an actuator link coordinated to the pawling means at one end with operative 60 connection at its other end to the cutter carrier and associated manipulator, a slot through the stationary structure for guidance of the securing strip between the feed drum and pressure roller, and flexible pusher means operatively connecting 65 the means aforesaid to the actuator mechanism of the binding device.

24. A binding device in accordance with claim 8, including a relatively stationary structure in the head of the pivotal jaw; a manipulator afforded slidable guidance by said stationary structure; a flexible pusher attached at its forward end to the manipulator; and means attached to the other end of said pusher operatively coordinating the latter to the actuator mechanism of 75 the binding device, said means comprising a fork

member including spaced legs; dogging claws at the free ends of said legs having opposingly-directed heel projections, laterally directed pins carried by said projections, recoil springs intermediate said pins and rigid anchorage means in the movable jaw cup-sections, and other stop projections in said cup-sections engageable by the dogging claws to limit the recoil movement of the flexible pusher and associated parts.

25. A binding device in accordance with claim 8, including a plane transformer device for turning the path of progression of the securing strip as it approaches the head of the movable jaw, said device consisting of a flattened arcuately-shaped tube having the entrant and exit ends twisted into right-angled relation, means for securing said device in the pivotal jaw, and a tapering longitudinal split in the exit portion of said device to facilitate withdrawal of the securing strip therefrom.

26. A binding device in accordance with claim 8, including a manipulator embodying a channel-like body-portion, a slot transversely through one flange of said body portion affording slidable guidance for a binder tape cutter member, latch means releasably coupling the cutter member to the manipulator for concurrent movement with the latter, spaced arms projecting forwardly from the other flange of the manipulator body-portion, said arms having opposed roundings for camming coaction with cooperative binder-tape narrowing means fulcrumed in the pivotal jaw head, a stepped extension with a lug integral with one arm, an angular extension from the other arm with a similar lug at a different level to the first mentioned one, said lugs serving to actuate opposed narrowing levers and compacting jaws in the rigid jaw head when the device jaws are alternately closed, and an angled tappet below the angled extension aforesaid for opening the trap-door device beyond its normal limit of pivotal movement concurrent with actuation of the compacting jaws.

27. A binding device in accordance with claim 8, including stepped fingers in one jaw head for coaction with slidable hold-down devices in the other jaw head, each said device embodying a movement limiting section, a medially anchored buffer spring influencing said devices outwards, and opposed coactive inclinations in the respective fingers and devices effective to initiate lateral narrowing of the binder tape.

28. A binding device in accordance with claim 8, including coactive binder-tape narrowing levers pivoted on a common axis scissor-fashion, each said lever embodying a notched heel portion at one end, a composite arcual serrated and plain section at the other end with an associated outer-offset and an inner clinching-tooth, a bow spring having its ends engaged in the lever heel portions effective to normally hold said levers in open position, and means coactive with the outer offsets operative to close said levers with the arcual ends in proximate engagement.

29. A binding device in accordance with claim 8, including a reciprocating carrier in the pivotal jaw, spring means normally retracting said carrier inwardly of the jaw head; a flat cutter member having a forward knife edge, said member being supported in a corresponding-section slot through the carrier; a latch device pivoted to the carrier, adjoining one side of the cutter member, and embodying a section engageable in a suitable notch in said member; a recoil spring attached intermediate the cutter member

inner end and a stationary anchorage in the pivotal jaw; and means whereby said cutter member can be manually shifted when the latch device aforesaid is released.

30. A binding device in accordance with claim 8, including, in the rigid jaw head, spaced upper and lower shelves; an arbor engaged through said shelves and rigidly connected between the jaw head and lower shelf; a tubular shaft on said arbor with free passage through the upper shelf; binder-tape narrowing levers pivotal on the tubular shaft, above the upper shelf, and intermediate stops on said shelf for limiting their angular opening; binder tape compacting levers pivoted on the tubular shaft above the lower shelf, and means rigidly connecting the narrowing and compacting levers for operation in unison; vertically spaced binder-tape spiraling and securing-strip compacting-severing jaws freely pivoted on the tubular shaft between the shelves aforesaid with an intervening stationary striker block, a coil spring on the tubular shaft influencing said jaws to open position; and means whereby the respective narrowing and compacting levers, as well as the compacting-severing jaws, are successively moved to closed position.

31. A binding device in accordance with claim 8, including, in the rigid jaw head, spaced and rigidly connected pairs of pivotal binder-tape narrowing and associated compacting levers; each said narrowing lever embodying a notched heel portion at one end with an arcual serrated part and a plain section part at the other end; each said compacting lever having a plain heel portion at one end and an arcual plain surfaced section at the other end with a grip notch thereon; coupler rods rigidly connecting the aligned heel portions of the respective pairs of levers; and recoil means connecting one pair of the levers for normally influencing all of said levers to open relation.

32. A binding device in accordance with claim 8, including in the rigid jaw head, a stationary striker member having a concaved outer active edge functional to initiate and effect wrapping of the securing-strip; vertically spaced binder-tape narrowing and compacting and securing-strip severing jaws respectively, pivotally mounted above and below the striker member; one of said jaws having an arcual end of vertically grooved formation to define a claw, and a groove in said end coactive with the striker member concaved edge; the other of said jaws having an arcual reduction for coaction with the first mentioned jaw claw portion, to limit the closure thereof, and a grooved end having a shearing edge inclined to the vertical for cutting the securing-strip; a laterally directed cam projection from each jaw; a coil spring about the pivot of said jaws having one terminal portion engaging the outer side of one jaw with the other terminal portion similarly engaging the other jaw for normally influencing them into open relation; and means coactive with the cam projections for effecting closure of the jaws.

33. A binding device in accordance with claim 8, including, in the rigid jaw head, a trap-means for gripping the free end of the binder tape to withdraw same from supply after an initial closure of the rigid and pivotal jaws, said means comprising a movable channel-section structure having the upper flange projecting beyond the lower and bent down to define a guide, means in said structure affording journal bearing for a device embodying spaced arms, angularly-related

extensions of said arms with the outer faces roughened for grip coaction with the underside of the structure upper flange; a lateral projection from one of said extensions; a manually-movable recoil means normally holding the trap means in active position; and means whereby the spaced arms are rocked inwards incidental to cutting of the binder tape upon a second closure of the pivotal jaw.

34. A binding device in accordance with claim 8, including, in the rigid jaw head, a movable trap-device for gripping the free end of the binder tape, means affording slidable guidance for the device along the jaw comprising a medial slot along the inner arcual wall of said jaw with flanking notches proximate the jaw head end; opposingly-related manipulators each embodying a grip section, a central cup, a stub slidable along the slot aforesaid and a retainer shank with a wider terminal section engaging the trap-device; and a buffer spring seating in the respective manipulator cup-sections whereby said manipulators are engaged in the flanking notches or relatively collapsed for progression along the medial slot aforesaid.

35. A binding device in accordance with claim 8, including opposed guard devices at the rigid and pivotal jaw heads, the guard device associated with the rigid jaw head, a stirrup-like springy wire, said wire embodying spaced coils with a connecting loop, means for attaching said loop to the jaw head with the coils partially seating in a suitable orifice in said head, divergent portions from the outer ends of the coils with 5 arcual continuations merging into straight extensions, and angularly contoured loops at the ends of said extensions; the opposing guard device for the pivotal jaw comprising pivotal flanking springy wire components each embodying a stem with a stop-shoulder and an angularly-shaped head, an inwardly directed bend at the lower end of the stem, spring means laterally below the pivotal jaw head for coaction with the respective stem inward bends for normally influencing the 10 components aforesaid upwards; and means limiting upward movement of the first mentioned guard device.
